UNITED STATES PATENT OFFICE

OTHO C. DURYEA, OF WATERBURY, CONNECTICUT, ASSIGNOR TO O. C. DURYEA CORPORATION, OF WILMINGTON, DELAWARE, A CORPORATION OF DELAWARE

CAR CONSTRUCTION

Application filed October 29, 1927. Serial No. 229,767.

This invention relates to railway cars and more particularly to a railway hopper car.

It is an object of this invention to provide a novel hopper car structure embodying a longitudinal center member which is mounted for movement relative to the car structure.

Another object of this invention is to provide a car structure of the type embodying a draft and buffing member extending substantially the length of the structure, the latter being provided with novel means for distributing draft and buffing forces exerted on said member.

Another object is to provide a novel bolster structure particularly adapted for use in hopper cars embodying a longitudinally movable center member.

A further object is to provide novel means for yieldingly resisting movement of the center member relative to the car body.

A further object of the invention is to provide novel means for yieldingly resisting relative movement of the center member and coupler whereby the capacity of the striking plate may be materially increased.

Another object is to provide novel stop means for positively limiting the relative movement of the center member.

A further object is to provide a car structure of the longitudinally movable center member type embodying stop means having a differential movement whereby the thrust resulting from relative movement of the center member is equally resisted adjacent the opposite ends of the structure. The above and other objects will appear more fully hereafter in the detailed description.

One embodiment of the present invention is shown in the accompanying drawings, but it is to be expressly understood that these drawings are for purposes of illustration only and are not designed as a definition of the limits of the invention, reference being had to the appended claims for this purpose.

In the drawings,—

Fig. 1 is a longitudinal sectional view through a portion of a hopper car structure embodying the present invention;

Fig. 2 is a horizontal sectional view and Fig. 3 is a vertical sectional view showing

one type of yielding means which may be employed in accordance with the present invention;

Fig. 4 is a transverse sectional view, with parts broken away, through one of the hoppers;

Fig. 5 is a detail sectional view illustrating one type of stop means which may be employed;

Fig. 6 is an end view, partly in section and with parts broken away, of one type of bolster construction which may be employed in accordance with the present invention;

Fig. 7 is a transverse sectional view taken on the line 7—7 of Fig. 2; and

Fig. 8 is a drawn out perspective view of one type of train slack means which may be employed in accordance with the present invention.

Referring more particularly to Figs. 1, 4 and 6, the structure constituting the present invention comprises a car body of the hopper type which is mounted on suitable trucks (not shown), by means of center plates 10 which are preferably attached, as by means of rivets 11, to the lower face of a body bolster 12. In order to employ a large scale drawing, a portion only of the car structure has been shown in Fig. 1. It is to be understood, however, that the same construction is employed at both ends of the car. Suitable doors 13, 14 are provided for the hoppers but the particular construction of these doors constitutes no part of the present invention.

Extending between the bolsters, and in the form shown substantially the length of the car structure, and mounted for longitudinal movement relative thereto, is a center member constituting a draft and buffing beam. In the embodiment illustrated, the center member comprises a pair of channels 15 which are rigidly secured together at a plurality of points, by means of suitable tie plates 16 and other members to be described hereafter.

It is desirable that the center member occupy the same relative position with respect to the car structure as that heretofore occupied by the center sills of hopper cars now in use. For this purpose it is desirable for the center member to pass through a suitable

opening or openings in the body bolsters and cross bearers. Yielding means are employed for resisting relative movement of the center member, and preferably, though not necessarily, said means are associated directly with the bolsters, so that draft and buffing forces exerted on the center member are thrown on said bolsters. Means are therefore associated with the bolsters for insuring that the forces exerted thereon, by relative movement of said center member, will be distributed to the car structure without damage to the same.

As shown more clearly in Figs. 1 and 6, the novel bolster comprises a diaphragm 17 which is secured along its upper edge, in any suitable manner, to the lower surface of the hopper floor sheet 18 and to the lower flanged edge of said diaphragm is suitably riveted a cover plate 19. Diaphragm 17 is provided adjacent the lower central portion thereof with an opening 17a in which is positioned a center brace 20 that may be formed as a casting. The lower surface of brace 20 is fixedly attached, as by means of rivets, to the cover plate 19, and is provided adjacent the bottom thereof with two laterally disposed and vertically extending flange portions 20a which are secured, as by means of rivets, to the lower edges of a longitudinal hood sheet 21 to be described more fully hereinafter. The upper end of the center brace 20 is secured, as by means of rivets, to the longitudinal hood sheet 21 and the structure is preferably further strengthened by means of a reinforcing angle 22, that is substantially bow-shaped, and which is secured to the diaphragm 17 and said hood sheet. In the form shown, rivets which extend through aligned openings in the center brace casting 20, the hood sheet 21, and the reinforcing angle 22, are employed for rigidly securing these portions one to the other, the upper surface of the center brace being preferably rounded to conform to the inner surface of the longitudinal hood sheet. The vertically disposed portion of center brace 20 is materially less in width than the width of the opening 17a in the diaphragm, and since said center brace is centrally disposed in the opening, sufficient space is provided between the outer vertical walls of said center brace and the hood sheet 21 for the passage of channels 15 of the center member. The inner faces of the webs of said channel members are adapted for sliding engagement with the outer faces of the central, vertical portion of the center brace 20, whereby lateral movement of the center member is prevented. The lower flanges of channels 15 are adapted to bear on transversely extending webs or ridges formed on the laterally projecting portions of the center brace 20, while suitable guiding members 23 (Fig. 6) are fixedly attached to the inner surface of the hood sheet in a position to slidably engage the

upper flanges of said channels 15, whereby the center member is guided at the bolster against movement in a vertical plane.

In order to distribute the forces exerted on the bolster to the remainder of the car structure, the longitudinal hood sheet 21 is extended inwardly from the bolster and through the hopper floor sheet 18 for a suitable distance, said hood sheet being rigidly secured to the floor sheet. Preferably, the outer portions of the lower edges of the longitudinal hood sheet are flanged laterally as at 21a (Fig. 6) and are secured, as by means of rivets, to the upper surface of the cover plate 19. In the form shown, the hood sheet extends inwardly to a cross bearer 24 and is rigidly secured thereto, but it is to be understood that said hood sheet may have any desired length and may even extend from one bolster to the other. The hood sheet also serves as a torque arm to prevent twisting of the bolster.

In structures heretofore employed, the outer end of the longitudinal hood sheet has terminated at the hopper floor sheet 18 since in said structures the center sill, which is riveted to said hood sheet, prevents draft and buffing forces from deflecting the plate bolsters. Moreover, hood sheets heretofore employed have had a form in cross section that is substantially dish-shaped. In the present structure, however, the center member, which also embodies some of the functions of a center sill, is adapted for movement relative to the bolsters and excessive forces placed thereon are distributed to the car structure by the novel hood sheet disclosed herein, or the equivalent thereof. Due to this function of the hood sheet, the same is substantially U-shaped in cross section, the arms of the U being sufficiently long to extend downwardly below the lower surface of the center member. These arms also constitute a portion of the side walls for the hoppers, as is indicated at 21b in Fig. 4. Preferably, suitable guides 25 are secured to the inner surface of the hood sheet at selected points to engage the upper flanges of channels 15 and to prevent buckling of the same both horizontally and vertically.

Novel means are provided for securing train slack. Referring more particularly to Figs. 1, 7 and 8, said means comprise a striking plate 26 rigidly secured to the outer ends of channels 15. A striking plate guide 27 is secured to the end of the body structure to support and guide the striking plate and the channels 15. Suitable openings 28 are provided in the striking plate 26 for receiving the usual coupler key 29 which extends through the shank 30 of the coupler 30a. Intermediate the inner end of the coupler shank and the inner face of the rear wall of the striking plate 26 is a cap 31 that is slidably mounted in a pocket 26a formed in said striking plate. Cap 31 is provided with

a flanged portion 31a which constitutes a bearing surface for a plurality of slidably mounted members, such as pins 32, that have abutting engagement therewith, and slidably extend through openings 26b in the striking plate 26. The inner ends of the pins 32 extend into pockets 33 formed in a follower 34 for a purpose to be described hereinafter. Movement of the coupler shank 30 inwardly, relative to the striking plate, is transmitted through cap 31 and pins 32 to the follower 34. The extent of movement of coupler shank 30 is positively limited, however, by means of key 29 and walls of openings 28 in striking plate 26 and by engagement of cap 31 with the striking plate.

Novel means are provided for yieldingly resisting relative movement of the center member with respect to the remainder of the car structure. Preferably, said yielding means are so constituted that the travel of the longitudinal center member relative to the remainder of the car structure is greatly in excess of the travel of standard draft gears now in use. Referring more particularly to Figs. 2 and 3, the yielding means may comprise a plurality of coil springs 35 which have engagement adjacent their outer ends with follower plate 34 and extend inwardly between the webs of the channels 15 through a suitable opening in the center brace 20 to a follower 36 that is slidably mounted in said opening in the center brace. The outer end of follower 36 is provided with a flange 36a which normally engages an inwardly projecting flange 20b formed on a portion 20c that projects inwardly toward the center of the car structure from the inner face of center brace 20 and which may be formed integrally with the latter if desired.

Under normal conditions resilient members 35 maintain flanges 36a and 20b in engagement, and also maintain follower 36 in engagement with a suitable stop 37 that is rigidly secured, as by means of rivets, to the webs of channels 15. Resilient members 35 also maintain follower 34 in engagement with the inner end of striking plate guide 27 and in engagement with a flanged beam 38 which extends transversely of the inner end of the striking plate and beneath the same. The beam 38 is held against movement longitudinally of the car structure by means of tie rods or bars 39 suitably secured at their outer ends to said beam and at their inner ends to the bolster. Resilient means 35 also act through follower plate 34 and pins 32 to maintain cap 31 closely in engagement with the inner end of the coupler shank and to maintain the forward edge of key 29 in engagement with the outer walls of openings 28 formed in the striking plate and channels 15.

Intermediate the bolster and the follower 34 is a member 40 which may be fixedly se-

cured, as by means of rivets, to the webs of channels 15. Member 40 constitutes a stop adapted to engage the adjacent face of the bolster to positively limit relative movement of the center member in one direction; it serves as a tie plate for the channels 15; and it constitutes a guide and supporting member for the resilient elements 35.

In order to facilitate assembly of the parts, the striking plate, which serves as a tie plate for the outer ends of the channels, is provided in the bottom thereof with an opening 26c through which pins 32 and cap 31 may be inserted for assembly purposes. Followers 34 and 36, and stop 37, may also be provided with suitable openings 41 to permit the use of bolts for holding springs 35 compressed during the assembly operation.

Operation.—If a buffing force be exerted on coupler head 30a, such a force tends to move the coupler to the left, as viewed in Figs. 2 and 3, relative to the remainder of the car structure. Relative movement of the coupler in this direction is yieldingly resisted by means of cap 31, pins 32, follower 34 and resilient means 35. Key 29 goes solid on striking plate 26 and cap 31 is bottomed in pocket 26a, whereupon the force tends to produce, or produces, relative movement between the center member and the remainder of the car structure. This relative movement of the center member is resisted by follower 34, resilient means 35 and follower 36, which is held against movement by its engagement with the projecting portion 20c of center brace 20, and by the resilient elements at the opposite end of the car. Since the travel of the yielding means is relatively great, the buffing force is gradually absorbed without damage to the car structure. In the event that the buffing force is unusually great, stop 40, and stop 37 at the other end of the car, will engage the adjacent faces of the bolsters and positively limit relative movement of the center member before the resilient means 35 goes solid.

It will be noted that the relative movement of the center member does not increase the train slack, i. e., relative movement between cars of the train, since this slack is determined by the movement of the coupler relative to the center member, which movement is positively limited and may be of any desired extent. Train slack, and hence movement of the coupler, is preferably maintained very limited relative to the movement of the center member with respect to the remainder of the car structure. A certain amount of train slack is necessary in order to prevent simultaneous action of cars of a train either in starting or stopping, but this slack is preferably of small extent and as stated, in the present invention, may be varied as desired.

If a draft force is exerted on coupler 30a, such a force will move the coupler, and hence

- the center member, to the right as viewed in Figs. 2 and 3. Relative movement of the center member causes stop 37 to act through follower 36 to compress the resilient members 35, the opposite end of said resilient members being held against movement by engagement of follower 34 with the striking plate guide 27 and beam 38. The resilient elements at the other end of the car, act simultaneously to resist relative movement of the center member. If the draft force is excessive, stop 37 will engage the inner end of projecting portion 20c of the bolster and stop 40, at the other end of the car, will engage the adjacent bolster to positively limit relative movement of the center member.
- The center member constitutes a rigid beam, but due to its great length it has been found that the stops 40 and 37 should be positioned at different distances from the adjacent faces of the bolster if over-solid blows, resulting from buffing forces, are to be distributed equally to the opposite end portions of the car structure. Thus, stop 37 is secured to channels 15 in a position such that normally it is closer to the adjacent face of the bolster than the stop 40. If relative movement is imparted to the center member by a buffing force which moves the latter to the left, as viewed in Fig. 2, stop 37, at the other end of the car, will engage the adjacent bolster before stop 40 engages its adjacent bolster. The elasticity, or compressibility, of the center member is such, and the relative positions of the stops 37 and 40 are so selected with respect to this compressibility, that the over-solid buffing blows are equally distributed on the opposite end portions of the car structure.
- There is thus provided a hopper car embodying a long travel center member, said travel being secured without an increase in the train slack. Preferably, the train slack is very limited but may be varied to meet various operating conditions. Means are provided whereby draft and buffing forces exerted on the center member are distributed to the car structure without likelihood of permanently deforming or damaging any of the elements, such as the body bolsters. The latter embody novel means for permitting movement of the center member therethrough without loss of load supporting strength. The novel center brace transmits the load to the center plate and trucks, thereby relieving the center member at this point from transmitting any appreciable load to the center plate. If desired, however, members 23 may be so formed or positioned that the center plate will be rigidly supported or backed by channels 15. In order to secure the desired travel of the resilient means the same are preferably of such length as to extend through the bolster. If a single resilient member is employed the expense is materially greater than

that of three smaller springs of the same capacity. Moreover, the center brace may be so formed, when three resilient members are employed, as to more evenly distribute the load on the center plate. The center brace constitutes a guide for the resilient members and coacts with member 40 to maintain the resilient members with the centers of the same substantially at the apices of a triangle, the centers of the two upper springs being located in a single substantially horizontal plane. The inner end of the center brace constitutes a stop for follower 36 and also serves to receive over-solid blows imparted by stop 37.

The novel cap 31 and pins 32 enable an unusually strong striking plate to be employed, thereby increasing the capacity of the same. The use of said cap and pins also permits resilient members 35 to be used to yieldingly resist relative movement of the coupler with respect to the center member. Friction resulting from engagement of guides 25 with the upper flanges of the channels 15 coacts with resilient members 35 to yieldingly resist relative movement of the center member. Novel stop means are provided which include members that embody the functions of a tie plate and a guide for the resilient members. Preferably, the stop means are so mounted as to have a differential movement in order to compensate for the elasticity of the center member.

While only one embodiment of the present invention has been described and illustrated, it is to be expressly understood that the invention is not limited to the form shown in the drawings. The yielding means for resisting relative movement of the center member may be employed in other than hopper cars as well as the means for securing train slack. Moreover, various types of yielding means, or energy dissipating means, may be employed for resisting relative movement of the center member. The travel of the center member, and hence of the yielding means, may be varied to suit the operating conditions and the type of car in which the same is used. For example, in passenger cars it may be desirable to provide for greater travel of the center member than in hopper cars. The train slack may also be varied to meet the requirements of particular trains or working conditions. If desired, the couplers may be mounted for movement in both directions relative to the center member. For example, the means disclosed in my co-pending application Serial No. 79,449, filed January 5, 1926, may be employed for this purpose, or means of the character disclosed in my co-pending application Serial No. 23,111, filed April 14, 1925, may be provided. Various changes may be made in the details of the body structure and in the shape of the rolled members 15. Reference will therefore be had to the

appended claims for a definition of the limits of the invention.

What is claimed is:—

5. 1. In a car structure, body bolsters, a longitudinal center member extending substantially the length of said structure and mounted for movement relative to said bolsters, yielding means for resisting movement of the center member relative to the bolsters, and means centrally secured to said bolsters and body structure and extending inwardly from the bolster for transmitting draft and buffing forces exerted by the yielding means on the bolster to the car structure, said force transmitting means each terminating and being secured to said body structure at points intermediate the bolsters.
10. 2. In a hopper car structure, body bolsters, a draft member extending between said bolsters and mounted for movement relative to the bolsters, means for yieldingly resisting relative movement of the draft member, and a longitudinal hood sheet extending from one of said bolsters to said body structure and adapted to coact with the bolsters to resist the thrust produced by relative movement of said draft member, said hood sheet also constituting a torque arm for the bolster.
15. 3. In a hopper car structure embodying a cross bearer structure intermediate its ends, a body bolster, a draft member extending substantially the length of the structure and mounted for movement relative to said bolster, means for yieldingly resisting movement of the draft member relative to the bolster, and rigid means extending inwardly from the bolster and terminating at said cross bearer, said rigid means being secured to the body structure adjacent said cross bearer structure for resisting the thrust produced by relative movement of the draft member, and being secured to the bolster substantially intermediate the outer extremities of the same.
20. 4. In a hopper car structure, a body bolster, a center member extending substantially the length of said structure and mounted for movement relative to said bolster, means for yieldingly resisting movement of the center member relative to the bolster, coupler means secured to the center member, and a longitudinal hood sheet rigidly secured to the bolster and extending inwardly through the adjacent hopper bottom for resisting the thrust produced by relative movement of the center member.
25. 5. In a hopper car structure, a body bolster, a draft member extending substantially the length of said structure and mounted for movement relative to the bolster, means for yieldingly resisting movement of the draft member relative to the bolster, said means including a resilient member disposed adjacent one end of the draft member and adapted to exert thrust directly on the bolster and longitudinal

disposed means secured to the bolster and telescopically disposed with respect to the draft member for resisting the thrust produced by relative movement of said draft member.

6. In a car structure, body bolsters, a continuous draft member mounted for movement relative to said bolsters, means for yieldingly resisting relative movement of the draft member, and means secured to one of said bolsters at points above and below the draft member and extending inwardly therefrom, said last named means terminating at a point intermediate said bolsters and having fixed engagement with the body structure for transmitting draft and buffing forces, exerted on said draft member, to said structure.

7. In a car structure having a plurality of hoppers, a body bolster, a draft member extending through said hoppers and mounted for movement relative to said bolster, means for yieldingly resisting relative movement of the draft member, and means extending through one or more of said hoppers and rigidly connected adjacent the outer end thereof to said bolster for strengthening the latter, whereby the bolster may effectively resist the thrust produced by relative movement of the draft member.

8. In a car structure embodying a hopper, transverse members including a body bolster and a cross bearer, a continuous draft member mounted for movement relative to said body bolster and cross bearer, means for yieldingly resisting movement of the draft member relative to said bolster, and a longitudinal hood sheet extending through said hopper and secured to said bolster and cross bearer.

9. In a car structure having a hopper, transverse members including a body bolster, a draft member extending substantially the length of said structure and mounted for movement relative to said bolster, a cover plate for said bolster and a longitudinal hood sheet extending through said hopper and fixedly secured to said bolster and cover plate.

10. In a railway car structure, a body bolster including a center brace, a draft member extending substantially the length of said structure and mounted for movement relative to said bolster, means for yieldingly resisting movement of the draft member relative to the bolster, and longitudinal strengthening means for the bolster including a member fixedly secured to said center brace.

11. In a car structure of the longitudinally movable center member type including yielding means for resisting relative movement of the center member, a striking plate secured to the center member, a follower for the yielding means, coupler means including a coupler shank operatively connected to the striking plate, and a plurality of pins opera-

tively connected to said follower and coupler shank for transmitting movement of the latter, relative to the striking plate, to said follower.

- 5 12. In a car structure, a body bolster, a draft member extending substantially the length of said structure and mounted for movement relative to the bolster, yielding means for resisting relative movement of the center member and bolster, said yielding means including a plurality of coil springs mounted with the centers of the coils of a plurality of said springs substantially at the apices of a triangle, and means including a 10 coupler movably connected to said draft member, said yielding means being adapted to resist movement of the coupler relative to the draft member.

- 15 13. In a car structure, a body bolster, a draft member extending substantially the length of said structure and mounted for movement relative to said bolster, yielding means for resisting movement of the draft member relative to the bolster, said yielding means including three coil springs having their centers disposed in two planes, and means including a coupler movably connected to said draft member, the movement of said coupler relative to the draft member being resisted by said yielding means.

- 20 14. In a car structure, a center member extending substantially the length of said structure and adapted for movement relative thereto, yielding means for resisting relative movement of the center member, and stop means having differential movement for positively limiting relative movement of the center member whereby over-solid blows are distributed equally to the opposite end portions of said structure.

- 25 15. In a car structure having bolsters, a draft member extending substantially the length of said structure and mounted for movement relative to said bolsters, means for yieldingly resisting relative movement of the draft member and bolsters, and stop means adapted to engage said bolsters to positively limit movement of the draft member in either direction, said stop means having differential movement whereby over-solid buffering blows are equally distributed to said bolsters.

- 30 16. In a car structure of the longitudinally movable center member type embodying yielding means for resisting relative movement of the center member in either direction, a stop member carried by the center member and adapted to engage the bolster to positively limit relative movement of the center member, said stop member constituting a tie plate for the center member, and a guide for said yielding means.

- 35 17. In railway draft rigging, sills mounted for frictional movement with respect to the underframe, cushioning means between said sills, a coupler with a stem disposed be-

tween said sills, means for connecting the stem to the sills, a block disposed between the stem and the cushioning means for transmitting forces therebetween to stress said cushioning means to provide for cushioning the movement of the coupler relative to the sills, and means on the underframe, for stressing said cushioning means upon movement of the sills with respect to the underframe.

40 18. In railway draft rigging, sills movably mounted with respect to an underframe, springs mounted between said sills for cushioning relative movement between said sills and underframe, a front follower engaging said springs, stop means on the underframe normally engaged by said follower, a casting connected to said sills, a coupler with its stem housed in said casting, key means intersecting said stem for transmitting forces between it and said sills, and follower means disposed between the rear of said stem and the front follower and passing through an aperture in the rear of said casting for transmitting buffering forces to said front follower.

45 19. In railway draft rigging, sills mounted beneath a vehicle underframe for longitudinal movement with respect thereto, means mounted between said sills for cushioning movement thereof with respect to the underframe, a combined striking, sill tie and cheek plate casting mounted between and connecting the ends of said sills, a coupler stem received in said casting, a block with an extension passing through said casting into engagement with the cushioning means, the front of said block being normally engaged by said coupler stem for receiving buffering forces therefrom to transmit them to the cushioning means upon movement of the coupler with respect to said sills, and means intersecting the stem, combined casting and draft sills for transmitting forces from the stem to the sills.

50 20. In railway draft rigging, sills movably mounted with respect to an associated underframe, resilient means mounted between said sills, follower means for said resilient means, stop means for said follower means mounted between said sills, stop means on the underframe cooperating with said follower means upon movement of the sills with respect to the underframe, a coupler, the stem of which extends between said sills, a key extending through said stem and sills, said sills being formed with elongated slots receiving said key and permitting limited movement thereof longitudinally of the sills, and a block disposed adjacent the rear of said coupler stem for transmitting force to the resilient means upon inward movement of the coupler.

55 21. In railway draft rigging, sills slidably mounted on an associated railway vehicle underframe for longitudinal movement with respect thereto, means disposed between said
